UNITED STATES PATENT OFFICE.

JOSEPH N. KLEMA, OF AUSTIN, MINNESOTA.

LANTERN.

1,323,698.

Specification of Letters Patent.

Patented Dec. 2, 1919.

Application filed June 21, 1919. Serial No. 305,784.

To all whom it may concern:

Be it known that I, JOSEPH N. KLEMA, a citizen of the United States, residing at Austin, in the county of Mower and State 5 of Minnesota, have invented certain new and useful Improvements in Lanterns, of which the following is a specification, reference being had to the accompanying drawings.

This invention relates to certain improvements in lanterns and has relation more particularly to a top or dome therefor; and it is an object of the invention to provide a novel and improved top or dome including means whereby the upper end portion 10 of the globe or chimney of a lantern is effectually engaged in a manner to maintain said globe or chimney in applied position.

It is also an object of the invention to provide a novel improved device of this general character wherein the dome or top has arranged therein a yieldingly supported ventilator serving as a holding means for the globe or chimney of the lantern, together with means whereby the ventilator 15 may be adjusted as desired.

The invention consists in the details of construction and in the combination and arrangement of the several parts of my improved lantern whereby certain important 20 advantages are attained and the device rendered simpler, less expensive and otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawings, wherein:

40 Figure 1 is a fragmentary vertical sectional view illustrating a dome or top for a lantern constructed in accordance with an embodiment of my invention, a globe or chimney being shown operatively engaged 45 therewith.

Fig. 2 is a view partly in top plan and partly in horizontal section of the structure as illustrated in Fig. 1.

Fig. 3 is a view similar to Fig. 1 but illustrating a further embodiment of my invention, and

Fig. 4 is a view in top plan of the body of the dome or top.

As particularly disclosed in Figs. 1 and 2 55 of the accompanying drawings, my improved dome or top comprises a cylindrical

body portion 1 having its lower or inner marginal portion defined by an outstanding skirt 2. The skirt 2 is adapted to be engaged in a conventional manner with the 60 upper end portion of the frame F of any desired type.

The upper portion of the body 1 is intersected by the radially disposed flat strip or bar 3 provided at substantially the axial 65 center of the body 1 with an opening 4 through which is disposed an elongated shank or bolt 5. The bolt or shank 5 extends axially of the body 1 and is provided at its lower end with a fixed head or enlargement 6.

Threaded upon the central portion of the shank or bolt 5 is a nut or stop 7 which engages the inner or under face of the strip or bar 3 whereby the bolt or shank 5 is held 75 against upward movement.

8 denotes a disk substantially snugly fitting within the lower portion of the body 1 and having its marginal portion defined by the downwardly directed flange 9. The 80 central portion of the disk 8 is provided with an opening 10 through which the bolt or shank 5 is loosely directed so that the disk 8 is capable of movement longitudinally of said bolt or shank 5. 85

The disk 8 is also provided with an annular series of openings 12 partially closed by the upwardly inclined plates or wings 14 struck from the disk 8 and whereby the 90 openings 12 are produced.

Overlying the upper or outer end of the body 1 is a cap 15 herein disclosed as concavo convex in form and the central portion of said cap 15 is provided with an opening 16 through which the upper or outer end portion of the bolt or shank 5 is loosely directed. Threaded upon the upper or outer end portion of the bolt or shank 5 is the nut or stop 17 contacting with the outer face of the cap 15. Interposed between the cap 15 and the member or bar 3 is an expandible member 18 herein disclosed as a coiled spring encircling the bolt or shank 5. The member 18 constantly urges the cap 15 toward the nut or stop 17 and by moving said 100 nut or stop 17 longitudinally of the bolt or shank 5, the cap 15 may be adjusted toward or from the body 1 as the occasions of practice may require.

The wall of the body 1 is provided with 110 the openings 19 through which the products of combustion may escape and which prod-

ucts also pass through the openings 12 in the disk 8 hereinbefore referred to.

In practice the upper or outer end portion of the globe or chimney G of the lantern 5 is engaged within the flange 9 of the disk 8 and through the instrumentality of the expandible member 11 said globe or chimney G is effectively held in working position by the disk 8. The yielding movement of 10 the disk 8 also facilitates the requisite engagement of the globe or chimney therewith.

The member 18 also operates to maintain the member or bar 3 in desired position because should said member or bar 3 expand 15 under the influence of excessive heat, the member 18 will serve to return the member or bar 3 to normal position as it cools.

In the embodiment of my invention as illustrated in Figs. 3 and 4 the body 1^a has 20 its upper marginal portion defined by an inwardly directed flange 20 provided at substantially diametrically opposed points by the recesses or notches 21.

Substantially midway of its length the 25 body 1^a is intersected by the flat member or bar 3^a having disposed through the central portion thereof the elongated bolt or shank 5^a. The bolt or shank 5^a is held in desired position by the member or bar 3^a through 30 the instrumentality of the clamping nuts 22 threaded upon the bolt or shank 5^a and engaging the opposite faces of the member or bar 3^a. By proper adjustment of the nuts 22, the bolt or shank 5^a may be adjusted 35 longitudinally as the necessities of practice may require.

The cap 15^a at substantially diametrically opposed points and adjacent its periphery is provided with the depending or inwardly 40 directed arms 23 terminating in the outwardly directed lugs or feet 24 adapted to contact with the inner face of the flange 20. In applying the cap 15^a in position the lugs or feet 24 are first passed through the recesses or notches 21 and said cap 15^a is then 45 partially rotated.

The lugs or feet 24 are maintained in contact with the flange 20 through the instrumentality of an expandible member 18^a interposed between the cap 15^a and the upper or outer nut 22. As herein disclosed the member 18^a comprises a coiled spring conoidal in form with its smaller end downwardly or inwardly directed.

55 The disk 8^a is substantially the same construction as hereinbefore set forth relative to the disk 8 and operates in the same manner and for the same purpose as said disk 8 under the influence of the expandible member 11^a interposed between said disk 8^a and the member or bar 3^a.

From the foregoing description, it is thought to be obvious that a lantern constructed in accordance with my invention is 60 particularly well adapted for use by reason

of the convenience and facility with which it may be assembled and operated and it will also be obvious that my invention is susceptible of some change and modification without departing from the principles and spirit 70 thereof and for this reason I do not wish to be understood as limiting myself to the precise arrangement and formation of the several parts herein shown in carrying out my invention in practice except as hereinafter 75 claimed.

I claim:

1. A dome for a lantern comprising a tubular body, a bar extending across the interior of said body, a shank disposed through 80 the bar at substantially the axial center of the body and provided with an enlargement at its inner end portion, a disk slidably mounted upon the shank and provided with openings, and means for constantly urging 85 said disk toward the enlargement of the shank.

2. A dome for a lantern comprising a tubular body, a bar extending across the interior of said body, a shank disposed 90 through the bar at substantially the axial center of the body and provided with an enlargement at its inner end portion, a disk slidably mounted upon the shank and provided with openings, and means for constantly urging said disk toward the enlargement of the shank, the marginal portion of the disk being defined by a downwardly directed flange.

3. A dome for a lantern comprising a tubular body, a bar extending across the interior of said body, a shank disposed 100 through the bar at substantially the axial center of the body and provided with an enlargement at its inner end portion, a disk 105 slidably mounted upon the shank and provided with openings, means for constantly urging said disk toward the enlargement of the shank, a cap coacting with the outer end of the body, and an expandible member interposed between the cap and the bar. 110

4. A dome for a lantern comprising a tubular body, a bar extending across the interior of said body, a shank disposed 115 through the bar at substantially the axial center of the body and provided with an enlargement at its inner end portion, a disk slidably mounted upon the shank and provided with openings, means for constantly urging said disk toward the enlargement of 120 the shank, and means for holding the shank normally against endwise movement with respect to the bar.

In testimony whereof I hereunto affix my signature in the presence of two witnesses. 125

JOSEPH N. KLEMA.
